UNITED STATES PATENT OFFICE.

RUSSELL HUFF, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,087,018.

Specification of Letters Patent.

Patented Feb. 10, 1914.

Original application filed July 26, 1909, Serial No. 509,594. Divided and this application filed July 25, 1913. Serial No. 781,190.

To all whom it may concern:

Be it known that I, RUSSELL HUFF, a citizen of the United States, and resident of Detroit, in the county of Wayne and State of Michigan, have invented certain new and useful Improvements in Hydrocarbon-Motors, of which the following is a specification.

This application is a division of application Serial No. 509,594, filed July 26, 1909, and the invention relates to hydrocarbon motors of the sleeve valve type.

One of the objects of the present invention is to arrange the valve sleeves so that they are free from the side thrust of the pistons.

Another object of the invention is to provide an annular valve chamber that is closed at both ends and is entirely separate from the combustion space of the motor except through the inlet and exhaust ports which are controlled by the valve sleeve or sleeves within the chamber.

Another object of the invention is to so construct a motor of the sleeve valve type that the inner and outer members that form the annular valve chambers will have no joints throughout the parts on which the valve sleeves slide and with the joints between these members located at the upper and lower ends of the respective valve chambers.

Another object of the invention is to so construct a motor of the sleeve valve type that the spark plugs or other ignition devices and the water connections for the head may be located in the top of the head in an accessible position, while at the same time the head and the surrounding casing, between which the annular valve chamber is formed, may be suitably connected to close the upper end of the valve chamber.

Another object of the invention is to make the parts forming the valve chambers readily detachable to facilitate machining and to make the valves easily accessible.

Other objects will appear from the following description taken in connection with the drawings, which form a part of the specification, and in which,

Figure 1 is a vertical sectional view of a motor embodying this invention, being taken on the line 1—1 of Fig. 2; and Fig. 2 is a section on the line 2—2 of Fig. 1, with parts shown in plan.

Referring to the drawings, each cylinder of the motor illustrated comprises two principal members, an outer member 10 of cylindrical form, and an inner member 11 arranged concentrically within and spaced from the member 10, thus forming an annular valve chamber 12 between the members. This valve chamber 12 is closed at its lower end by means of a complete circumferential joint 13 between the members 10 and 11, and it is closed at its upper end by means connecting the adjacent upper ends of said members 10 and 11. This connecting means may be of any suitable form so that it does not extend entirely over the top of the inner member, and it is shown in the form of an annular flange 14 which fits the top of the outer member and is secured, as by screws 15 and a ring 16, to the upper end of the inner member. A ring 17 engages the upper side of the flange 14 and is clamped against the flange and removably secured to the upper end of the member 10 as by bolts 18. The flange 14 thus forms a closure for the top of the valve chamber 12 and the inner and outer members are readily detachable.

The upper part of the inner member 11 forms the head of the cylinder, having a transverse water-cooled part 19 which performs this function. By reason of the fact that the connecting means between the upper ends of the members does not cover the part 19 of the inner member, the spark plug or other ignition device 20 may be arranged in the center of the part 19 and a water connection 21 may also be mounted in this part. Thus both the spark plug and the water connection are accessible through the ring 17 and its coöperating connecting members. The spark plug is thus arranged approximately in the center of the combustion space 22 of the motor where it is most effective and the water is taken from the extreme upper end of the inner member so that no air pockets in the water jacket are possible. The inner member 11 is formed with inlet and outlet ports 23 which communicate with the combustion space 22 and with the valve chamber 12 substantially midway between the ends of the latter, and the outer member 10 has ports 24 which also communicate with the valve chamber 12 and are aligned with the ports 23. As shown, there is a circula-

tion of water around the ports 23 through ducts 25 in the connection 26 formed between the parts of the inner member 11 which are above and below the ports 23. It will be understood that the walls of the valve chamber 12 are accurately machined and ground and if desired suitable packing rings 27 and 28 may be employed for the purpose of more perfectly closing the ports in the valve sleeve about to be described.

10 One or more valve sleeves may be arranged within the valve chamber 12 for the purpose of coöperating with the ports 23 and 24 in the inner and outer members respectively, and in the drawings two such sleeves, 29 and 30, are shown. These sleeves are respectively provided with ports 31 and 32 which coöperate with the ports 23 and 24 as above suggested, for the purpose of opening and closing these ports to operate the motor on the four stroke cycle.

15 The cylinder of the motor may be suitably arranged below the valve chamber forming members 10 and 11, and in the present instance the cylinder 33, in which the piston 34 slides, is formed as an integral part of the inner member 11, being suitably water-jacketed, as at 35. The whole of the motor as above described is mounted upon a suitable crank case 36, the upper part only of which is shown in the drawings, and diagrammatically illustrated are the connecting rod 37 and crank shaft 38, which latter is of course mounted in the crank case.

20 35 The valve sleeves 29 and 30 may be arranged to slide in any suitably manner upon their respective ground surfaces, and in the drawings the inner valve sleeve is operated by means of a sliding rod 39 connected to an eccentric 40 by means of a connecting rod 41. The outer valve sleeve 30 is provided with an extension 42 which is connected to a rod 43 by means of the reinforcing piece 44. The rod 43 is operated from an eccentric 45 by means of a connecting rod 46. The eccentrics 40 and 45 are mounted upon the eccentric shafts 46 which are driven from the crank shaft by means of the usual two-to-one gearing 47.

25 50 It is believed that the operation of the valve sleeve in the embodiment of the invention shown will be obvious, it being understood that in the drawing the piston and the other working parts are shown in the upper dead center position of the exhaust stroke and the ports in the sleeves and in the inner and outer members will coöperate at the proper times for the operation of the motor on the four stroke cycle. It will be seen that the valve sleeves are so arranged that they are not subjected to the side thrust of the pistons, and being located in carefully closed chambers, the walls of which are unbroken save for the ports and rings, and 60 which are closed above and below the valve

sleeves, leakage along the surfaces of the valves will be reduced to a minimum.

It will be understood that suitable means for feeding oil to the above sleeves may be provided as in the motors shown in said application, Serial No. 509,594, and, if desired, other features of said motors may be adopted in coöperation with the motor shown in this application. For instance, while I have shown the sleeve operating mechanism as 75 mounted below the cylinder, it will be obvious that other operating mechanism may be employed and if desired located above the cylinder, as shown in said application. It is also to be understood that this invention is 80 not to be limited to a plurality of superposed valve sleeves for each cylinder, since an engine of this type may be operated with a single sleeve or with a plurality of sleeves which are not superposed. It is further obvious that various changes may be made in the details of construction without departing from the spirit of this invention, and it is, therefore, to be understood that this invention is not to be limited to the specific 85 construction shown and described.

Having thus described my invention, what I claim and desire to secure by Letters Patent is:

1. In a hydrocarbon motor, the combination of inner and outer concentrically arranged cylindrical members, the outer of said members extending above the upper end of said inner member, means extending within the upper end of said outer member and connecting said members together, said members and said means forming an annular valve chamber between the members with complete circumferential joints at the upper and lower ends of said chamber, and a movable valve sleeve in said valve chamber, said members and said sleeves having coöperating ports.

2. In a hydrocarbon motor, the combination of inner and outer concentrically arranged cylindrical members, said members being separated to form an annular valve chamber between them and being joined together at the lower end of said valve chamber to close the latter, and said members having aligned inlet and exhaust ports in their side walls, a valve sleeve in said chamber coöperating with said ports, and means connecting the upper contiguous ends of said members comprising a flange and rings removably securing said flange to said members.

3. In a hydrocarbon motor, the combination of an outer cylindrical member, an inner cylindrical member separated from the outer member and forming therewith an annular valve chamber between said members, said inner member being closed at its upper end and forming a water jacketed cylinder head and having transverse inlet and outlet

- ports below said closed end, said outer member having ports coöperating with the ports of the inner member, said members having a complete circumferential joint at the extreme lower end of said chamber and below said ports, means connecting the upper ends of said members and forming a complete circumferential closure for the upper end of said valve chamber and leaving the closed head part of said inner member exposed, and ignition and water connections in the exposed part of said inner member whereby said connections are accessible, and a movable valve sleeve in said valve chamber.
4. In a hydrocarbon motor, the combination of an outer cylindrical member, an inner cylindrical member separated from the outer member and forming therewith an annular valve chamber between said members, said inner member having transverse inlet and outlet ports below its upper end and communicating with the combustion chamber and with said valve chamber, said outer member having ports coöperating with the ports in said inner member and also communicating with said valve chamber, said members having a complete circumferential joint at the lower end of said valve chamber, and means connecting the upper ends of said members and forming a complete circumferential closure for the upper end of said valve chamber, said means including a ring detachably secured to one of said members, the removal of which ring permits of the separation of one member from the other, and a movable valve sleeve in said valve chamber.
5. In a hydrocarbon motor, the combination of inner and outer concentrically arranged cylindrical members, means connecting one of said members to the other, said members and said means forming an annular valve chamber between the members and surrounding the cylinder head with complete circumferential joints at the upper and lower ends of said chamber, and a movable valve sleeve in said valve chamber, said members and said sleeve having coöperating ports.
6. In a hydrocarbon motor, the combination of inner and outer concentrically arranged cylindrical members, means connecting one of said members to the other, said members and said means forming an annular valve chamber between the members and surrounding the cylinder head with complete circumferential joints at the upper and lower ends of said chamber, and a movable valve sleeve in said valve chamber, said members and said sleeve having coöperating ports, and means entering said valve chamber at the lower end thereof for operating said valve sleeve.
7. In a hydrocarbon motor, the combination of inner and outer concentrically arranged cylindrical members and means connecting one of said members to the other, said members and said means forming an annular valve chamber between the members with complete circumferential joints at the ends of the chamber, and one of said members having the cylinder wall in which the piston operates cast as an integral part of said member and said member having ports in its side walls, the other of said members also having ports, a movable valve sleeve in said valve chamber, and means for operating said sleeves.
8. In a hydrocarbon motor, the combination of inner and outer concentrically arranged cylindrical members and means connecting one of said members to the other, said members and said means forming an annular valve chamber between the members with complete circumferential joints adjacent the ends of the chamber, the inner of said members having the cylinder wall in which the piston operates formed as an integral part of said inner member, and said inner member having inlet and exhaust ports in its side walls, said outer member having ports in line with the ports of said inner member, a valve sleeve arranged in said valve chamber and having ports coöperating with the ports in said members, a piston in said cylinder, and means for operating said valve sleeve from the piston.
9. In a hydrocarbon motor, the combination of an inner cylindrical member forming a substantially cylindrical combustion space and a closed end at the upper end of said space, said member having inlet and exhaust ports communicating with the sides of said combustion space, a piston operating below said combustion space, an outer cylindrical member surrounding and arranged concentric with the inner member and forming therewith an annular valve chamber above and below said ports, said members making a complete circumferential joint at the extreme lower end of said valve chamber, and means connecting said members together at their contiguous upper ends and completely closing the upper end of said valve chamber, said outer member having ports in line with the ports in said inner member, a valve sleeve arranged in said valve chamber and having ports adapted to coöperate with the ports in said members, and means moved by the piston for operating said valve sleeve.
10. In a hydrocarbon motor, the combination of a head member and a cylindrical member concentric therewith and spaced therefrom to form an annular valve chamber, a valve sleeve in said chamber, a flange on said head member fitting said cylindrical member, and a ring secured to said cylindrical member and engaging the upper side of said flange.

11. In a hydrocarbon motor, the combination of a head member and a cylindrical member concentric therewith and spaced therefrom to form an annular valve chamber which is cut off at the bottom from the gases in the cylinder, a valve sleeve in said chamber, a flange on said head member closing the top of said chamber, a ring engaging the upper side of said flange, and means securing said ring to said cylindrical member and adapted to clamp the ring against said flange.

12. In a hydrocarbon motor, the combination of a head member and a cylindrical member concentric therewith and spaced therefrom to form an annular valve chamber which is cut off at the bottom from the gases in the cylinder, a valve sleeve in said chamber, a flange on said head member closing the top of said chamber, a ring engaging the upper side of said flange, and means

ber, there being a joint at the bottom of the chamber permitting separation of the parts, a valve sleeve in said chamber, a flange on said head member fitting said cylindrical member and closing the top of said chamber, a ring engaging the upper side of said flange, and means whereby said ring is secured to said cylindrical member and clamped against said flange. 23

In testimony whereof I affix my signature in presence of two witnesses.

RUSSELL HUFF.
